FOOD SERVER

Stephen Lipka, Melbourne, Fla.

Application February 21, 1958, Serial No. 49,753

Term of patent 14 years

(Cl. D44—10)

FIG. 1

I claim:

The ornamental design for a food server, as shown.
